UNITED STATES PATENT OFFICE.

FREDERICK W. ZURBURG, OF CHICAGO, ILLINOIS.

SLED.

SPECIFICATION forming part of Letters Patent No. 231,746, dated August 31, 1880.

Application filed July 16, 1880. (No model.)

To all whom it may concern:

Be it known that I, FREDERICK W. ZURBURG, of Chicago, in the county of Cook and State of Illinois, have invented a certain new and useful Improvement in Sleds, of which the following is a specification.

The object I have in view is to produce a simple and cheap child's sled, which can be readily taken apart or "knocked down," so that it can be packed in a small space for storage or transportation, and will therefore be much cheaper to handle than the sleds now made, can be easily put together without other tools than a wrench, and will be exceedingly strong in construction.

My invention consists in the several novel features embodied in my improved sled, as fully hereinafter explained, and pointed out by the claims.

In the accompanying drawings, forming a part hereof, Figure 1 is a perspective view of the sled; Fig. 2, a vertical cross-section of the same through the center of the forward cross-bar, looking toward the tail of the sled; and Fig. 3, a vertical section from front to rear through the left-hand-side forward joint, looking inwardly.

A represents the runners, B the standards, C the cross-bars, and D the board, of the sled. The runners are bent from wood, and are of the usual construction. The standards B are of cast metal, and are made of any suitable design. Each standard at its bottom terminates in a plate, *a*, which is the width of the runner, and rests thereon. Lugs *b* project downwardly from the sides of the plate *a*, and inclose between them the runner, the standard being secured to the runner by wood-screws *c* passing through said lugs, or by a rivet or a bolt. The plate and lugs form a very stiff joint between the runner and the standard.

Near its upper end each standard has an inwardly-projecting lug, *d*, with outwardly-bevelled side edges, which lug slides, like a stove-leg fastening, in a dovetail way, *e*, formed in a cast-metal plate, *E*. One of such plates is secured to each end of each cross-bar by a wood-screw, *f*.

The extensions of the standards above the

lugs *d* abut solidly against the ends of the 50 cross-bars.

At the ends of the rear cross-bar, bolts (not shown) pass downwardly through the cross-bar, the plates *E*, and lugs *d*, and have nuts on their lower ends, by tightening which the 55 parts are drawn firmly together.

The runners are bent upward and rearward at the front ends, and rest on the ends of the forward cross-bar.

Bolts *i* pass down through the ends of the 60 runners, through the forward cross-bar, the plates *E*, and lugs *d*, and are secured by nuts *k* on their lower ends. These bolts are like those that pass through the rear cross-bar, except that the latter only pass through the cross-bar, plates *E*, and lugs *d*.

The cross-bars are of wood, and the board is secured to them by wood-screws.

A front round, *l*, is held between the curved front ends of the runners by means of holes 70 or sockets bored through or in the runners, and without other fastenings.

Now, it will be seen that by removing the four bolts the sled can be taken apart and packed in about one-fourth of the space it occupies when set up. The sled can also be easily put together, and is strong and durable.

What I claim as my invention is—

1. In a knockdown sled, the combination of the metal standards *B*, having dovetail lugs 80 *d*, the metal plates *E*, secured to the cross-bars, and having dovetail ways or grooves *e*, and the bolts passing through the cross-bars and through said plates and lugs, substantially as described and shown.

2. In a knockdown sled, the standards having lugs projecting under the ends of the cross-bars, in combination with the runners bent back upon the forward cross-bar, and the bolts *i* passing through the ends of the runners and securing the forward cross-bar and standards together, substantially as described and shown.

3. A knockdown sled wherein the standards have laterally-projecting lugs or wings 95 extending under the ends of the cross-bars, and the runners are bent backward upon the ends of the forward cross-bar, in combination

with four bolts that secure the parts removably together, substantially as described and shown.

4. The knockdown sled described, consisting of runners A, standards B, cross-bar C, board D, plates E, and round l, the standards being secured to the runners by lugs that inclose such runners, and the cross-bars, stand-

ards, and runners being held together at the top of the sled by four bolts, substantially as set forth and shown.

FREDERICK W. ZURBURG.
